DISPLAY STAND

Jacob De Vries, 908 W. 18th Ave., Vancouver,
British Columbia, Canada

Filed May 22, 1967, Ser. No. 7,219

Term of patent 14 years

(Cl. D80—9)

FIGURE 1 is a perspective view of a display stand, showing my new design, one corner of the base being broken away for convenience of illustration; and

I claim:

The ornamental design for a display stand, substantially as shown.
